UNITED STATES PATENT OFFICE.

JAMES S. NICHOLS, OF ATLANTA, GEORGIA.

SUPERHEATER.

1,340,074.

Specification of Letters Patent. Patented May 11, 1920.

Application filed May 12, 1915. Serial No. 27,638.

To all whom it may concern:

Be it known that I, JAMES S. NICHOLS, a citizen of the United States, residing at Atlanta, in the county of Fulton and State 5 of Georgia, have invented new and useful Improvements in Superheaters, of which the following is a specification.

My present invention relates to improvements in steam superheaters and is especially adapted for use in connection with 10 locomotive boilers.

The primary object of the present invention is to provide certain improvements in superheaters of the class shown and described 15 in my prior application, Serial No. 871,930, filed November 13, 1914, which embodies a valve, a fire-box superheater and superheater units within the boiler flues and which also embodies means whereby saturated or superheated steam may be used 20 separately or mixed and a circulation of superheated steam is maintained through the superheater, steam from the superheater being returned to the boiler when the same is not being used.

The present invention provides a valve of novel and improved construction for controlling the flow of superheated steam either to the engine cylinders or to the 30 boiler when superheated steam is not being used; it provides improved means for introducing the saturated steam from the boiler to the fire-box superheater unit to prevent back-flow of superheated steam 35 from the superheater units in the flues; it provides means for flooding the superheater in firing up the boiler to prevent burning or damage to the superheater structure before the generation of sufficient steam to 40 protect the superheater; it provides means whereby the supply of all saturated steam to the superheater can be cut off to enable repair or replacement of parts of the superheater while the boiler is under steam 45 pressure; and it also provides superheater units of improved construction for the boiler flues whereby the construction and repair thereof are facilitated.

To these and other ends, the invention 50 consists in certain improvements, and combinations and arrangements of parts, all as will be hereinafter more fully described, the novel features being pointed out particu-

larly in the claims at the end of the specification.

In the accompanying drawings:

Figures 1 and 2 represent longitudinal sections of the front and rear portions of a locomotive boiler equipped with a superheater embodying the present invention.

Fig. 3 represents a vertical section of the valve which controls the flow of superheated steam from the superheater, together with the pipe by which the superheated steam is returned to the boiler when superheated steam is not being used.

Fig. 4 is a top plan view of the valve with the top cover removed.

Fig. 5 represents a section on the line 5—5 of Fig. 3.

Fig. 6 represents a section of the valve on the line 6—6 of Fig. 3.

Fig. 7 represents a cross-section of the superheated steam return pipe showing one of the clamps by which it is attached either 75 to the valve or to the forward flue sheet.

Figs. 8 and 9 are detail views of the improved head for the pipes of the superheater unit.

Fig. 10 represents a transverse section 80 through one of the boiler flues showing a superheater element or unit therein and provided with a spacer between the pipes of the superheater unit and a clamp for binding together the pipes and supporting 85 them centrally within the flue.

Fig. 11 is a detail view of the separator or spacer for the pipes of the superheater unit.

Fig. 12 is a transverse vertical section 90 through the smoke box, showing the valve casing or header in elevation, and with the superheated steam pipes connected therewith partly broken away.

Fig. 13 is a plan view of the header and 95 associated parts shown in Fig. 12.

Similar parts are designated by the same reference characters in the several views.

The present invention provides improvements in superheaters which are capable of 100 use either in whole or in part in connection with steam boilers of various types. These improvements are especially applicable to steam locomotives, and the invention is shown so applied in the accompanying 105 drawings and will be hereinafter described.

in detail. It is to be understood, however, that the invention is not restricted to the precise construction shown, as equivalent constructions are contemplated and will be included within the scope of the claims at the end of the specification.

In the present instance, the boiler, which is of the locomotive type, comprises the cylindrical or barrel portion 1, the smoke-box 2, and the fire-box 3, fire tubes or flues 4 extending longitudinally within the cylindrical portion of the boiler and forming passageways for the products of combustion leading from the fire-box to the smoke-box. The ends of the flues or fire tubes are fitted into the front and rear tube sheets 5 and 6, respectively. In order to provide the maximum space for the superheater units and to avoid unduly enlarging the flue 10 openings in the rear flue sheet 6, the rear ends of the flues are preferably swaged or otherwise reduced, as at 7, so that the flues will be of a size to amply accommodate the superheater units, but the openings for these flues in the rear tube sheet 6 may be of the usual size.

The superheater comprises a number of superheater units which are contained in some of the flues or fire tubes of the boiler, the same being inserted into the flues from the forward ends thereof. Preferably, and as shown, each superheater unit comprises a number of pipes or tubes 8, 9 and 10, three pipes or tubes being shown in the present instance. Two of these pipes (the pipes 9 and 10 in the present instance) have their rear ends threaded into openings 11 and 12 which are formed in a head 13, the latter being composed preferably of a casting and having a return bend or channel 14 formed therein and establishing communication between the adjacent ends of the tubes or pipes 9 and 10. The head 13 has an opening 15 which is straight and extends therethrough from end to end, and the pipe 8 is slidably fitted into this opening. The pipe 8 is connected to one of the other two pipes of the superheater unit at the forward end of the unit, it being shown connected to the pipe 9 in the present instance by the return bend 16. The forward end of the remaining pipe 10 is connected by a bend 17 to the superheated steam controlling valve 18.

The pipes or tubes composing each superheater unit are held in properly spaced relation to permit the circulation of the heated gases between them by separators or spacers 19, these spacers being placed at suitable intervals longitudinally of the superheater unit. In using three pipes or tubes for each superheater unit, each spacer will have a set of three segmental recesses 20 in its periphery in which the respective pipes or tubes of the superheater unit are

seated whereby these pipes or tubes will be separated or held in properly spaced relation. The spacer or separator may also be formed with an opening 21 so as to avoid unduly obstructing the flow of the heated 70 gases. The pipes or tubes of the superheater unit are held or bound together at appropriate intervals by a suitable number of surrounding bands 22, each band being shown in the present instance as comprising 75 three similarly formed sections of metal which lie against the outer sides of the pipes or tubes, the sections of the band being united by rivets 23 or equivalent means, and feet or lugs 24 are formed at the 80 apices of the band to engage the inner wall of the flue whereby the superheater unit is supported and appropriately centered within the flue, thus avoiding obstruction to the passage of the heated gases and insuring 85 uniform action of the heat upon the superheater unit. In order to avoid burning or other injury to the corners of the head 13 where the pipes 9 and 10 are inserted therein, due to the action of the highly heated 90 gases, laterally projecting enlargements 25 are formed at opposite sides of the head 13 in rear of such corners whereby the highly heated gases flowing longitudinally within the flue will be deflected and hence prevented from striking directly against these 95 corners of the head.

Superheater units constructed in accordance with the present invention are capable of being readily repaired, as it is possible, 100 should either of the pipes 9 and 10 become defective, to withdraw these pipes 9 and 10, together with the head 13, from the flue by pulling the same forwardly therein, a suitable coupling 160 (as, for example, an ordinary 180° elbow) being provided for the pipe 8 at the bend 16 therein, the head 13 sliding longitudinally on the pipe 8, and the forward end of the pipe 8 which remains within the flue may be connected by a suitable union and a section of pipe of proper length to the coupling 26 and thence directly to the superheated steam controlling valve 18. To facilitate connecting the forward ends of the superheater units to the valve 18 115 and to also allow for expansion and contraction of the piping and other parts, ball joints 26 may be provided, as shown.

The superheater shown in the present instance not only comprises the superheater 120 units contained in the boiler flues, but the superheater units is also provided in the fire-box of the boiler. This fire-box superheater comprises outer and inner shells 27 and 28, the top and forward sides of which are preferably horizontal and vertical, respectively, and the rear walls of these shells are preferably inclined in order to accommodate the fire-box superheater to the firing of the boiler, as well as to insure the most efficient 125 130

action of the heat upon this superheater. The space 29 between the outer and inner shells 27 and 28, respectively, is a water space, and it is connected to receive water 5 from the water space of the boiler by a suitable pipe 30, and to return this water from the space or chamber 29 to the water space of the boiler by a suitable number of pipes 31, these pipes 31 preferably discharging 10 heated water at a point above the crown sheet 32. The interior of the inner shell 28 forms a steam chamber 33, and the pipes 8 of the superheater units in the boiler flues extend through the outer and inner shells 15 27 and 28 and communicate with the chamber 33 to receive saturated steam from the boiler. Saturated steam from the boiler is conducted into the chamber 33 of the firebox superheater unit by a pipe 34 which 20 leads from the steam dome 35 and is preferably provided with a manifold 36 and a suitable number of branch pipes 37 which lead therefrom and through the outer and inner shells 27 and 28, discharging saturated 25 steam from the steam dome into the steam chamber 33. These saturated steam supply pipes 37 are preferably extended downwardly to substantially the bottom of the steam chamber 33 in order that the saturated 30 steam will be introduced at the bottom of this chamber, and rising therein will maintain, in the bottom of said chamber, a body of saturated steam which will prevent the backflow of the relatively lighter superheated 35 steam from the superheater units in the boiler flues. In order to increase the efficiency of the boiler and at the same time protect the fire-box and superheater from becoming unduly heated, a water-jacketed 40 steel arch is placed in the fire-box of the boiler and between the fire therein and the rear side of the fire-box superheater unit. The water-jacketed steel arch in the present instance comprises a shell 38 having a water 45 chamber 39 which is connected by the pipe 40 to receive water from the water space of the boiler, and it is connected by the pipe 41 to the water space of the boiler at a relatively higher point to return the water, but heated 50 to a higher temperature, to the water space of the boiler. The water-jacketed steel arch is preferably formed with an opening 42 through which a portion of the heated gases may pass and become uniformly distributed 55 around the fire-box superheater. Also, a portion of the water heated in the chamber 39 is preferably conducted into the water space 29 of the fire-box superheater, pipes 43 and 44 being shown connecting the chambers 29 and 39 for this purpose. 60

In firing up the boiler, it is preferable or advisable to flood the superheater system with water to avoid burning or unduly heating the elements or units thereof before sufficient steam has been generated in the su-

perheater to protect such parts. To enable this to be accomplished, a pipe 45 is provided which connects with one of the pipes 37 leading to the steam chamber 33, and the pipe 45 is connected at 46 to the water space 70 of the boiler, the flooding of the superheater with water being controlled by a valve 47 which valve, however, is closed during the normal operation of the boiler under steam pressure. Means is also provided for cutting off the supply of all steam to the superheater should such become necessary owing to damage of any part of the superheater. As shown, a valve 48 is provided in the saturated steam supply pipe 34, this valve having a handle 49 which may be manipulated to close the valve from the exterior of the boiler shell. By closing the valve 48, the supply of all saturated steam to the superheater is cut off and it is thereby rendered 80 possible to remove or repair different parts of the superheater, and particularly the superheater units in the boiler flues, while the boiler is under steam pressure. In the normal operation of the boiler, however, 90 this valve 48 is open.

Saturated steam may be admitted to the engine cylinders by the dry pipe 50 under control of the throttle 51, as is usual. The pipe 50 is provided, however, at a suitable 95 point, preferably in the smoke-box of the boiler, with a fitting 52 to which the superheated steam controlling valve 18 is connected. This superheated steam controlling valve, according to the present invention, 100 comprises a casing 54, one wall 55 of which is provided with openings into which the pipes 17 leading from the superheater units in the flues are fitted, the casing being formed with a superheated steam chamber 105 56 into which the superheated steam from the flue units discharges. The valve casing is also formed to receive a valve which performs the function of controlling the return of superheated steam to the boiler and the 110 flow of superheated steam to the engine cylinders. In the construction shown, the valve has a cylindrical portion 57 which is reciprocable in a correspondingly formed portion of the valve casing and is provided with a transverse port 58 which is movable into and out of communication with ports 59 and 60 formed in the valve casing. A vent 61 may lead from one end of the valve 115 to the port 58 to avoid a compression or vacuum at such end of the valve as the latter is reciprocated. The valve also has a portion to control the flow of superheated steam to the engine cylinders, such portion in the present instance comprising a head 62 having a conical part 63 to coöperate with a conical seat 64 in the valve casing, and a cylindrical sleeve 65 extends below the conical portion of the head and fits closely 120 within a cylindrical portion 66 of the valve 125 130

casing. A port 67 leads from the chamber 68 which latter occupies a position between the conical seat 64 and the ports 59 and 60, this port 67 communicating with the fitting 52 which fitting is also attached to the dry pipe 50 and has an outlet 69 which serves to conduct either saturated steam or superheated steam, or both, to the engine cylinders. The superheated steam controlling valve has a rod 70 attached thereto, and this rod extends through a stuffing-box 71 in the lid or cover 72 of the valve casing 18, and suitable means is provided whereby the rod 70 and consequently the superheated steam controlling valve may be operated from the cab of the locomotive or from any other suitable point. In the present instance, a bell-crank lever 73 is provided, which is pivoted at 74 and is connected by a rearwardly extending rod 75 to a throttle lever 76, the latter being pivoted at 77 and provided with a suitable locking sector 78 whereby the superheated steam valve may be opened to any suitable point or closed and retained in any of these desired positions. The port 60 in the valve casing 54 is connected to return superheated steam to the boiler when superheated steam is not being used. As shown in Fig. 3, superheated steam is returned to the boiler by a return pipe 79 which forms a connection between the valve casing 54 and the tube sheet 5 and terminates at the latter. In Figs. 1 and 2 is shown a pipe 780 leading from the forward tube sheet 5 to the steam dome 35, and connected at its forward end with the valve casing 54 by a short return pipe corresponding to the pipe 79. The means for connecting the return pipe with the valve casing and tube sheet are preferably such as to facilitate the fitting of said pipe and also to allow for variations in alignment of the parts due to contraction and expansion or any other influences or strains to which they may be subjected in use. Thus, as shown most clearly in Fig. 3, each end of the pipe 79 is formed with a spherical surface 80 to engage a correspondingly formed seat in the tube sheet 5 and in the valve casing 54 surrounding the port 60, and devices are provided for clamping these ends of the pipe 79 into steam-tight engagement with the respective seats. As shown, each end of the pipe 79 has an enlargement 81, and a pair of yoke-shaped plates 82 and 83 is provided, these plates having openings 84 and 85 which enable the plates to be slipped over the pipe 79, and after the plates are applied, they are relatively rotated to carry the openings 84 and 85 out of register, as appears in Fig. 7. One of the plates (the plate 82 in the present instance) is also preferably provided with flanges 86 which are adapted to overlap certain edges of the plate 83 to prevent relative rotation between

them after they have been properly applied to the pipe 79. Bolts 87 extend through registering openings in the corners of the plates 82 and 83 and serve to clamp the ends of the pipe 79 in position.

The length of the superheated steam return pipe, and the precise details of some of the other parts of the connection, will, of course, vary considerably according to the requirements. Thus, there is shown in Fig. 3 a construction suitable for use in a stationary or other boiler installation involving a relatively long distance or space in the smoke box between the boiler flues and the smoke stack. In the case of a locomotive boiler, such as is shown in Fig. 1, this space is relatively short, and the design of the connections will be correspondingly modified to correspond to the other dimensions of the structure. Also, as above stated, in the case of a locomotive boiler provision is preferably made for delivering the returned superheated steam to the steam dome instead of discharging the same directly into the boiler at the forward tube sheet, as in the case of a stationary boiler.

The controlling valve in the casing 54 is operative to direct superheated steam from the chamber 56 to the boiler and also to direct and throttle the flow of superheated steam from said chamber to the outlet port 67.

When superheated steam is not being used, the valve occupies the position shown in Fig. 3, the supply of superheated steam to the engine cylinders being then cut off, and the superheated steam entering the chamber 56 from the superheater passes through the ports 58, 59 and 60 which are then in register and returns to the boiler by way of the pipe 79. The full quantity of superheated steam is supplied to the engine cylinders by raising the valve to its uppermost position, which carries the valve port 58 out of register with the superheated steam port 59 and the return port or passage 60, and carries the sleeve 65 to a point above the valve seat 64. The return of superheated steam to the boiler is at this time cut off, and the superheated steam is admitted from the chamber 56 through the opening in the valve seat 64 to the chamber 68 and thence to the outlet port 67, from which it passes into the fitting 52 and thence through the pipe 69 to the engine. In an intermediate position of the valve, shown in dotted lines in Fig. 3, the valve port 58 communicates, not only with the superheated steam port 59 and return port or passage 60, but also with the chamber 68 and consequently with the outlet port 67. When, therefore, the valve is moved downwardly from its uppermost position into the position shown in full lines in Fig. 3, to cause

the head 62 and sleeve 65 to close communication between the chamber 56 and outlet port 67, the valve port 58 immediately opens communication between the chamber 56 and both the outlet port 67 and return passage 60, and thereafter, as the valve is further depressed, closes communication between the chamber 56 and outlet port 67 and fully opens communication between 10 said chamber and the return passage 60 alone. It will thus be seen that in one extreme position of the valve superheated steam is admitted to the outlet and cut off from the boiler, that in the other extreme 15 position superheated steam is admitted to the boiler and cut off from the outlet, and that, as the valve is shifted from one extreme position to the other, communication from the superheated steam chamber is 20 maintained with both the outlet port and the return passage until one or the other is fully open.

In the operation of locomotives, it is desirable or necessary to start and stop the locomotive by the use of saturated steam, and to use saturated steam as a lubricant for the cylinders and their working parts. In such cases, the locomotive may be started by admitting saturated steam to the cylinders by opening the usual throttle 51 in the ordinary way, the superheated steam controlling valve being then set so as to return the steam circulating through the superheater to the boiler. Superheated steam 30 may then be admitted to the engine cylinders by opening the valve 18 which cuts off the return of superheated steam to the boiler and permit the superheated steam to flow into the pipe 69 through the fitting 52. In 35 cases where it is desirable or advantageous to use a mixture of saturated and superheated steam, the saturated steam controlling throttle 51 may be opened more or less, admitting saturated steam to the engine cylinders, and the superheated steam controlling valve 18 may also be opened to an extent to admit a suitable amount of superheated steam to the engine cylinders. Of course, the locomotive can be driven 40 by saturated steam alone or by superheated steam alone, and when saturated steam alone is used, a circulation of steam is maintained through the superheater, thus utilizing the full heating effect of the superheater in the generation of steam and avoiding damage or injury to the superheater. A safety valve 88 may be fitted in the cover 72 of the valve 18 to relieve any excessive pressure that may be developed in 45 the superheater.

I claim as my invention:—

1. In combination with a steam boiler and a superheater, a casing having a chamber to receive steam from the superheater, a 50 passage for conducting superheated steam

from said chamber to the boiler and having a port for admitting superheated steam from said chamber to an outlet for use, and a valve having a port to coöperate with said passage for conducting superheated steam 70 to the boiler, and a head to control and throttle the flow of superheated steam from said chamber to said outlet, the valve being operative to first open communication between said chamber and said passage and 75 to subsequently close communication between said chamber and said port when the valve is shifted.

2. The combination with a steam boiler and a superheater; of a casing having a 80 chamber to receive steam from the superheater; a superheated steam port communicating with said chamber, a passage for conducting superheated steam from said chamber to the boiler, and an outlet port 85 for admitting superheated steam from said chamber to an outlet for use; and a valve having a port movable into and out of communication with said superheated steam port and adapted to communicate with both 90 said passage and said outlet port or with said passage alone, said valve having also a portion adapted to admit superheated steam from said chamber to said outlet port when said valve port is out of communication 95 with said superheated steam port.

3. The combination with a steam boiler and a superheater; of a casing having a chamber to receive steam from the superheater, a passage for conducting superheated steam from said chamber to said boiler, and an outlet port for admitting superheated steam from said chamber to an outlet for use; and a valve having a port adapted to open and close communication between said 100 chamber and said passage alone or between said chamber and said passage and outlet port simultaneously; said valve having also a head adapted to open and close communication between said chamber and said outlet 105 port.

4. The combination with a steam boiler and a superheater; of a casing having a chamber to receive steam from the superheater, a passage for conducting superheated steam from said chamber to said boiler, and an outlet port for admitting superheated steam from said chamber to an outlet for use; and a reciprocatory valve having a portion adapted to open and close communication between said chamber and said passage alone or between said chamber and said passage and outlet port simultaneously; said valve having a second portion adapted to open and close communication between said chamber and said outlet 115 portion alone.

5. In combination with a steam boiler and a superheater, means for directing superheated steam from the superheater to the 130

- boiler and to a delivery outlet for use, said means including a steam controlling valve comprising a casing formed with a cylindrical seat and also a conical seat and having ports controlled by the respective seats and adapted to establish communication respectively between the superheater outlet and the boiler and between the superheater outlet and the delivery outlet, and a reciprocating valve member having a cylindrical portion operative in the cylindrical seat and having a port to coöperate with the port respective to said seat and also having a conical portion coöoperative with the conical seat.
6. In combination with a steam boiler and a superheater, means for directing superheated steam from the superheater to the boiler and to a delivery outlet for use, said means including a steam controlling valve comprising a casing provided with a cylindrical seat and also a conical seat and having ports controlled by the respective seats, said ports being adapted to communicate respectively with the steam space of the boiler and with the delivery outlet, and both ports being in communication with the outlet of the superheater, and a reciprocating valve member having a cylindrical portion operative in the cylindrical seat and provided with a port to coöperate with the port respective to said seat and also having a conical portion coöoperative with the conical seat, and a cylindrical sleeve adjacent to said conical portion and operative to pre-

vent flow of steam through said conical seat until the port in the cylindrical seat has been closed.

7. The combination with a boiler, of a superheater comprising superheater units 40 for the boiler flues and a firebox superheater unit having a steam chamber positioned opposite to the rear ends of the flues and connected to the superheater units as a header therefor, and means for conducting steam 45 from the boiler to the steam chamber in the firebox superheater, said means comprising a pipe extending downwardly through the top of said chamber to a point at or near the bottom thereof.

8. A superheater unit comprising superheater pipes, and a head containing a return bend passage to which the ends of certain of said pipes are connected and having an opening in which another of said pipes 55 fits slidably.

9. A superheater unit comprising superheater pipes, and a head containing a return bend passage to which certain of said pipes are connected and having exterior enlargements to protect from heat corners of the head adjacent to the points of connection of said pipes.

In testimony whereof I have hereunto set my hand in presence of two subscribing witnesses.
